(57) **CLAIM**

The ornamental design for an injection cannula array device as shown and described.

DESCRIPTION

FIG. 1.1 is an upper, left, rear perspective view of a first example of our new design for an injection cannula array device.

FIG. 1.2 is an upper, left, front perspective view thereof.
FIG. 1.3 is an upper, right, rear perspective view thereof.
FIG. 1.4 is a bottom plan view thereof.

FIG. 1.5 is a lower, right, rear perspective view thereof.
FIG. 1.6 is a lower, right, front perspective view thereof.
FIG. 1.7 is a lower, left, rear perspective view thereof.
FIG. 2.1 is an upper, right, rear perspective view of a second example of our new design for an injection cannula array device.

FIG. 2.2 is an upper, left, front perspective view thereof.
FIG. 2.3 is a bottom plan view thereof.

FIG. 2.4 is a lower, right, front perspective view thereof.
FIG. 2.5 is an upper, left, rear perspective view thereof.
FIG. 2.6 is a lower, right, rear perspective view thereof.
FIG. 2.7 is a lower, left, rear perspective view thereof.
FIG. 3.1 is an upper, right, rear perspective view of a third example of our new design for an injection cannula array device.

FIG. 3.2 is a bottom plan view thereof.
FIG. 3.3 is an upper, left, front perspective view thereof.
FIG. 3.4 is an upper, left, rear perspective view thereof.
FIG. 3.5 is a lower, right, front perspective view thereof.
FIG. 3.6 is a lower, right, rear perspective view thereof.
FIG. 3.7 is a lower, left, rear perspective view thereof.
FIG. 4.1 is an upper, right, rear perspective view of a fourth example of our new design for an injection cannula array device.

FIG. 4.2 is an upper, left, rear perspective view thereof.
FIG. 4.3 is an upper, left, front perspective view thereof.
FIG. 4.4 is a bottom plan view thereof.
FIG. 4.5 is a lower, right, front perspective view thereof.
FIG. 4.6 is a lower, right, rear perspective view thereof.
FIG. 4.7 is a lower, left, rear perspective view thereof.
FIG. 5.1 is an upper, left, rear perspective view of a fifth example of our new design for an injection cannula array device.

FIG. 5.2 is a bottom plan view thereof.
FIG. 5.3 is an upper, right, rear perspective view thereof.
FIG. 5.4 is an upper, left, front perspective view thereof.
FIG. 5.5 is a lower, right, front perspective view thereof.
FIG. 5.6 is a lower, right, rear perspective view thereof.
FIG. 5.7 is a lower, left, rear perspective view thereof.
